UNITED STATES PATENT OFFICE.

ALEXANDER Q. NASH, OF ST. LOUIS, MISSOURI.

SPARK-GAP DEVICE.

1,382,113.

Specification of Letters Patent. Patented June 21, 1921.

Application filed May 17, 1920. Serial No. 381,903.

To all whom it may concern:

Be it known that I, ALEXANDER Q. NASH, a citizen of the United States, residing at St. Louis, State of Missouri, have invented 5 certain new and useful Improvements in Spark-Gap Devices, of which the following is a specification.

This invention relates to means for intensifying and indicating the character of the 10 spark delivered to the cylinder of an internal combustion engine.

I am cognizant of the fact that previously patented devices of this class already exist and, in fact, the present invention constitutes 15 an improvement of the ignition detector and spark intensifier described and claimed in my Patent No. 1338521 issued to me April 27, 1920.

In the previous patent granted to me the 20 potential of the ignition current is increased for the production of a disruptive discharge by interposing a contact ball between two terminals, one of the terminals forming a seat for the ball and the other spaced from 25 the ball a sufficient distance to provide a properly proportioned spark gap.

The present invention is an improvement over the previously patented construction in that two spaced terminals are mounted upon 30 an insulating block. One of these terminals is in the form of a retainer for a freely movable contact ball, while the other terminal co-operates with the ball to form a spark gap and, at the same time prevents the ball from 35 jumping out of the retainer but without restricting its free movement in the retainer.

The particular advantages of the present 40 construction constituting this improvement reside in the co-operative functions of the spaced terminals and ball, whereby the said freely movable contact ball is confined within certain limits by its retainer and is maintained in the retainer by one of the terminals forming the spark gap with the ball.

45 In the drawings:

Figure 1 is a side elevation, in central section, through a device constructed in accordance with the present invention.

Fig. 2 is a front elevation thereof.

50 Fig. 3 is a top plan view.

Fig. 4 is a top plan view of a blank for a modified form of the device.

Fig. 5 is a front elevation of the modified form, and

55 Fig. 6 is a top plan view of the modified ball retaining terminal.

In detail:

The device, as herein shown in Figs. 1 to 3 inclusive, comprises an insulation block 1 upon which is mounted a ball retaining terminal in the form of a cup 2 carried by right angle bracket 3 held to the insulating block by the binding post screw 4 which passes through the insulation block 1 and carries a washer 5 held by the nut 6, the wire 8 being 60 retained on the binding screw post 4 between the nut 6 and another nut 7. The cup 2 may be secured to the bracket 3 by any suitable means such as soldering, welding, or the like, and holes 9 through the bottom of the cup 70 and the bracket provide for egress of dust and the like.

If desirable, the cup 2 and its attendant bracket 3 may be blanked and stamped in a single piece.

75 The cup 2 receives a contact ball 10 which is only of sufficient size to project above the side wall of the cup and yet be freely movable in the interior thereof. This contact ball 10 is retained within the cup 2 by a 80 terminal member 11 which projects out over the top in the manner shown and is spaced sufficiently from the ball to provide a properly proportioned spark gap without permitting the ball to jump out of the cup.

85 The terminal member 11 carries a right angle extension 12 seating against the insulation block 1 and having the slot 13 through which the binding post screw 14 is passed, a washer 15 and nut 16 securely 90 clamping the terminal member 11 in a properly adjusted position with respect to the ball 10. A similar nut 17 clamps the wire 18 between the nut 16 and said nut 17. By this arrangement the terminal member 11 may 95 be moved for the purpose of adjustment with respect to the ball 10 or for the purpose of removing and replacing the ball 10.

The disruptive discharge of current, whereby the potential of such current is increased takes place through the gap above mentioned, the gap being at all times properly ventilated by reason of its open construction.

100 In the modification shown in Figs. 4, 5 and 6 the parts are identical with those shown in Figs. 1, 2 and 3 with the exception of the ball retaining cup which, in this modification, is formed of a blank 19 having several arms 20 which are bent up at right 110 angles to the body of the blank, as shown in Figs. 5 and 6, with the result that a cup

21 is provided which has relatively open sides.

While the construction herein described provides for an inclosure of cup form for 5 the ball, it is nevertheless to be understood that various departures in the exact formation of the cup may be resorted to without avoiding the claims of the patent.

I claim:

- 10 1. In a spark gap device, spaced terminals, one forming a walled inclosure for a contact ball freely movable therein, and the other terminal maintaining the ball against displacement from said inclosure.
- 15 2. In a spark gap device, spaced terminals, one forming a supporting cup for a contact ball freely movable thereon, and the other terminal maintaining the ball against displacement from the ball supporting cup and 20 adjustable with respect to the cup to form the gap and permit removal and replacement of the ball.

3. In a spark gap device, spaced terminals, one forming a cup, a contact ball freely movable within said cup, and the other terminal forming a cup cover plate to prevent displacement of the ball from the cup and to form a gap with the ball. 25

4. In a spark gap device, spaced terminals, one comprising a flat central portion having 30 upturned arms, a contact ball freely retained on said central portions by said arms and projecting thereabove, and the other terminal providing a ball retaining means spaced from the ball to form a spark gap. 35

5. In a spark gap device, spaced terminals, one comprising a castellated ball receiving cup, a contact ball freely retained within said cup, and the other terminal spaced above said cup and ball to form a spark gap 40 and retaining the ball within the cup.

In testimony whereof I affix my signature.

ALEXANDER Q. NASH.
